Primary Examiner — Susan E Krakower*Assistant Examiner* — Lisa A Grabenstetter(74) *Attorney, Agent, or Firm* — Seyfarth Shaw LLP(57) **CLAIM**

The ornamental design for a maxi pad, as shown and described.

DESCRIPTION

FIG. 1 is a front perspective view of a maxi pad showing my new design; and,

FIG. 2 is a top plan view thereof.

The bottom view of the maxi pad, which is not shown in the drawing disclosure, forms no part of the claimed design.

The dash-dash broken lines represent portions of the maxi pad which form no part of the claimed design.

The dash-dash broken lines below the boundary depict unclaimed portions of the maxi pad.

The broken line that runs parallel to the uppermost claimed border of the design represents unclaimed stitching.
